T. DUYSENS.

OUTER COVER FOR PNEUMATIC TIRES FOR BICYCLES, MOTOR VEHICLES, AND THE LIKE,
APPLICATION FILED SEPT. 28, 1916.

1,295,014.

Patented Feb. 18, 1919.

UNITED STATES PATENT OFFICE.

TOSSANUS DUYSENS, OF MAASTRICHT, NETHERLANDS, ASSIGNEE OF ONE-HALF TO
RENE HUSTINX, OF MAASTRICHT, NETHERLANDS
OUTER COVER FOR PNEUMATIC TIRES FOR BICYCLES, MOTOR-VEHICLES, AND THE LIKE.

1,295,014.

Specification of Letters Patent. Patented Feb. 18, 1919.

Application filed September 28, 1918. Serial No. 122,629.

To all whom it may concern:

Be it known that I, TOSANUS DUYSENS, of Maastricht, Netherlands, have invented new and useful Improvements in Outer 5 Covers for Pneumatic Tires for Bicycles, Motor-Vehicles, and the like, of which the following is a specification.

This invention relates to a pneumatic tire cover for bicycles, motor-vehicles and the like, made of a material which, as in the usual covers, consists of a fabric such as 10 canvas or similar stuff coated with rubber. In the case of such known covers, the threads of the material lie diagonally to the direction of the circumference of the cover *i. e.*, the warp and weft threads are not parallel to the cross section of the cover and do not therefore lie vertically thereto. This had to be done because, with the usual method 15 of manufacture, the warp and weft threads have to be displaced one against the other in order to obtain a tubular ring from one piece, and this is only possible when the threads lie in the position above described. 20 It is self-evident that the connection between the warp threads and the weft threads must thereby be disturbed, and that in order to maintain such a condition in the connection, the connection must not be too resisting, and 25 it follows therefore that for such purpose a fabric only may be used, the threads of which are not too resisting and which permit with comparative ease, a disturbance in the connection.

According to this invention, the cover is 30 made up of a number of assembled narrow strips bent transversely around the pneumatic tube, said strips consist of woven material and rubber or the like and are joined together. The strips are shaped so as to 35 form, together, with the sides lying against each other, a closed smooth envelop for the airtube. If the strips are sewn together by consecutive zig-zag stitches, they then form 40 a hollow annular covering.

This construction of the cover makes it 45 possible to select any kind of fabric desired, while the joining of the warp and weft threads need not be interrupted, as is the case with the usual covering, whereby the further notable advantage is obtained that the more resisting warp threads can be arranged parallel to the cross section of the

cover, which is the direction in which the cover has to offer the greatest resistance.

The strips, in order to retain the annular form, are so shaped that they are narrower at the ends than in the center, so that when said strips are cut out of one piece, the warp of which consists of parallel threads, the longitudinal or warp threads contained in the lateral bulges of the strip are shorter than those which extend within the narrow ends of the strip. As this, however, would reduce the strength of the strip at the sides, the strips may be woven to the exact shape, so that the edges have a selvage.

After a layer of strips has been sewn to the shape of the cover, a second layer of similar strips may be arranged upon the former which may again be made in like manner and the separate strips of which may be so arranged that they cover the seams between the strip of the first layer while the same can also be sewn on to the strips provided underneath, whereby they are themselves attached, and secure the strips of the lowest layer together. It follows therefrom that it is not absolutely necessary to sew the strips of the lowest layer together. In this manner the cover may consist of a large number of layers, according to the strength, resistance and thickness required in the cover.

The extremities of the strips may lie parallel to the surface of the wheel, so that a flat ring is formed on both sides of the wheel by the envelop, while the felly is located between the two rings so formed. On the outer side of said rings a metallic ring can be provided in each case, and such metal rings, by means of pins which are fixed through perforations in the same on to the cover and the felly, can be tightened together so as to thus rigidly hold together the cover and the felly.

For the purpose of giving to the cover a greater resistance against lateral strains, flaps are provided on both sides in the interior of the cover, that is, between the airtube and the felly. Said flaps, which may be annular, are then pressed and held by the air pressure against the felly.

The fastening of such removable or fixed protector which forms the running surface, is effected in one or several of the lower layers,

whereby a particularly powerful fastening can be obtained.

In conclusion the invention refers to a special description of metallic pressure rings which consist in that the outer edge of said rings is bent approximately to the shape of the cover and thus increases the supporting surface and prevents the formation of sharp angle there.

10 The invention is illustrated in the accompanying drawing as follows:

Figure 1 shows part of a section through the wheel with the cover.

Fig. 2 a lateral view of said part and
15 Fig. 3 one of the strips spread out and on a smaller scale.

The air-tube 1, according to the mode of execution, is surrounded by an envelop which consists of three layers, 2, 3 and 4, 20 each of which is made of a number of strips 5, the position of which is indicated in Fig. 2, and the shape when flat, shown in Fig. 3.

Said shape is such that if the strips are bent according to the section shown in Fig. 25 1, and placed next to one another, the strips form together a smooth annular envelop for the air-tube 1, or the layer provided under the same. It is self-evident that for the purpose of fulfilling this object, the 30 strips need not be exactly of the form illustrated in Fig. 3 and that it suffices to connect the side of the strips next to one another when bent.

The strips of the various layers are sewn 35 together one under the other by zig-zag stitches while the strips of the upper layers next to said seam are sewn to the strips of the layer lying under it. The strips are arranged in such manner that the 40 seams of one layer are always covered by the strips of the layer lying under it, as is clearly shown in Fig. 2 where the strips of said layer, which are provided under the illustrated layer, are represented by dotted 45 lines.

The edges of the surrounding layers are formed parallel to the surface of the wheel as flat rings which lie over one another and against the flat sides of the felly 6. The 50 annular part of the outer layer 4, for the purpose of strengthening it, is further furnished with a ring 7 of similar material sewn on to it. Upon said rings, on both sides of the wheel, a metallic ring 8 is provided the outer edge of which is bent to the shape of the cover for the purpose of supporting the same when pressed in. In connection with these two rings 8 and the 55 annular parts of the envelop and the felly 60 provided between them, bolts 9 are pro-

vided which, when the nuts 10 are tightened, connect the felly with the cover.

Between the tube 1 and the felly 8, flaps or annular soft pieces 11, 12, which can be made of a material similar to that of the strips, are arranged, being secured to the inner sheet 2, and make a continuation of the envelop in the direction of the circumference of the tube. Said flaps are thus wedged firmly between the tube and the 70 felly when the tube is inflated, so that the whole arrangement offers a greater resistance to lateral strain.

The drawing also illustrates an annular cover protector 13 around the cover, which 75 by this mode of execution, conforms to the contour of the outer layer of the envelop or of the cover. Nevertheless said protector may be of any desired shape and be made removable from the cover in any 80 known manner. It is, however, advisable that the fastening should be between one or more of the lower layers, as hereinbefore mentioned already.

A cover embodying this invention might 85 be so constructed as to be secured to the felly and rim in the usual way, that is to say, the rings 7 might be formed into the customary edge beads to fit into the rim.

In addition to the advantages already 90 mentioned above, the cover, according to this invention, offers another advantage, namely that it can be easily repaired, while when one or more strips are damaged they can easily be replaced by new ones. Owing 95 to the arrangement of several layers each cover can also be strengthened as desired, without an entirely new strip being necessary for that purpose, which is also a great advantage in the manufacture of the covers. 100

Having thus fully described my invention, what I claim is:

An outer cover for pneumatic tires, comprising a plurality of superposed layers connected at their central portions but disconnected at their edge portions, in conjunction with a felly the side surfaces of which are engaged by the inner faces of the loose edge portions of the outer layers, while the peripheral surface of the felly is engaged by the loose edge portions of the inner layer, and means for securing the edge portions of the outer layers to the felly.

In testimony whereof I affix my signature in presence of two witnesses:

TOSSANUS DUYSENS.
